Arthur M. Zeillermayer, New York, N. Y.

Application June 28, 1944, Serial No. 114,243

Term of patent 3½ years

(Cl. D58—11)

To all whom it may concern:

Be it known that I, Wendy Weeks, a citizen of the United States of America, residing in New York city, county of New York and State of New York, have invented a new, original, and ornamental Design for a Combined Bottle and Display Holder Therefor, of which the following is a specification, reference being had to the accompanying drawing, forming part thereof, wherein,

Figure 1 is a front perspective view of a com-

bined bottle and display holder therefor, showing my new design.

Figure 2 is a similar view, showing the device as it appears with cover removed.

I claim:

The ornamental design for a combined bottle and display holder therefor, substantially as shown.

WENDY WEEKS.
